UNITED STATES PATENT OFFICE.

CAMPBELL P. HIGGINS, OF ROSELLE, NEW JERSEY.

MACHINE FOR FLANGING MANHOLES IN BOILERS, &c.

SPECIFICATION forming part of Letters Patent No. 558,072, dated April 14, 1896.

Application filed July 24, 1895. Serial No. 556,991. (No model.)

To all whom it may concern:

Be it known that I, CAMPBELL P. HIGGINS, a citizen of the United States, residing at Roselle, in the county of Union and State of New Jersey, have invented a new and useful Improvement in Machines for Flanging Manholes in Boilers, &c., of which the following is a specification.

This invention consists in a machine having certain features of construction and arrangement, hereinafter described and claimed, whereby flanging manholes in boilers, &c., can be more expeditiously and satisfactorily performed than has heretofore been the case.

15 In the accompanying drawings, Figure 1 represents in vertical section a sufficient portion of the machine for an understanding of the invention, a part of a boiler or drum to be operated upon being shown in position thereon preparatory to flanging the manhole therein. Fig. 2 represents a similar view with the parts in the position they assume when the flanging has been completed. Fig. 3 shows in side view and partial section one of the formers with which the flanging is effected. Fig. 4 represents a top view of the same. Fig. 5 represents a top view of the interior of the drum after the manhole has been flanged.

30 The machine is intended to be operated by hydraulic pressure, and has a base or body A, provided with a cavity a for the admission of water, as through a duct a', in which cavity is arranged a piston B, a suitable packing, as 35 at c, being employed to prevent the escape of the water around the piston.

The piston B is furnished with a central hole b, through which passes a rod C, that is secured at its lower end to the base A. A 40 packing d is attached to the piston surrounding said rod to prevent the escape of water through the hole, and the rod is preferably packed at d' in order that water may not escape around the lower end thereof. Upon 45 the upper end of the piston is secured a male former E having a hole therein for the passage of the rod C, the upper or entering portion e of which is shaped to fit the initial opening or hole (as an oval one, shown by dotted lines x in Fig. 5) that has been made in the boiler or drum F, which hole is to be expanded and the material around the same to

be formed into a flange f. Below the part e of the former is a frusto-conical portion e', which acts to expand the hole and produce 55 the flange, and below this part is preferably a portion e'', having a vertical periphery. Detachably secured to the upper end of the rod is a head-block or backing-block G, which may be circular, oval, or of other suitable form 60 in transverse outline, and combined therewith is a female former H in the shape of a ring loosely surrounding the rod C, the interior outline of which is the same in shape as the outline of the flange to be formed. 65

Preferably there is combined with the flange f a reinforcing-piece J, having an initial shape in transverse section such as shown in Fig. 1, the portion j of which is bent into a vertical position, as shown in Fig. 2, during 70 the flanging of the manhole K.

The operation of the machine is substantially as follows: The piston B being in its lowermost position, and the head-block G and female former H being detached, the 75 boiler or drum F is placed over the machine and the portion e of the male former E is inserted into the initial opening x, that has been made in the drum. The reinforcing-piece J is then passed over the upper end of 80 the rod C and adjusted in position on the drum, when the former H is placed upon said piece and the head-block G is screwed upon the rod C, thereby clamping the former H and piece J in place. Water is now forced through 85 the duct a' into the cavity a, and the piston B, with its attached male former E, is moved upward, thereby causing said former to expand the hole x and force the material surrounding the same into the form of a flange 90 f, the portion j of the piece J being bent upward at the same time, as shown in Fig. 2. After the flanging has been completed the head-block and former H are removed, when 95 the flanged drum can be taken off.

Although I prefer to make the former H separate from the block G, so as to use various formers with the said block, yet it will be readily understood that such former and block may be integral, if desired, it only being necessary to allow the rod C to pass through an unthreaded hole in the block G sufficiently far properly to receive a nut on its threaded end, which nut can be screwed

down to clamp the former upon the drum to be flanged.

What I claim as my invention, and desire to secure by Letters Patent, is—

- 5 1. The combination of a piston carrying a former; a stationary rod passing loosely through the same; a second former surrounding said rod and adapted to coöperate with the first former; and a backing-block dependentably secured to the rod, substantially as and for the purpose specified.
- 10 2. The combination of a piston carrying a former having its entering portion shaped to fit the hole to be expanded, and provided

with an adjoining frusto-conical portion for 15 expanding the hole and flanging up the material surrounding the same; a stationary rod passing loosely through said piston and former; a second former loosely surrounding said rod and adapted to coöperate with the 20 first former; and a detachable head-block secured to the rod and backing the second former, substantially as set forth.

CAMPBELL P. HIGGINS.
